CHECKERBOARD

Garry E. Bennett, Hawthorne, Nev., and
Laura M. Bennett, Long Beach, Calif.

Application April 14, 1944, Serial No. 531,014

4 Claims. (Cl. 273—136)

1

The present invention relates to improvements in checker boards and has for an object to provide an improved checker board and checker holding devices in association with the checker board for the purpose of making checkers, and other like games and puzzles, available to bedridden patients in any degree of convalescence.

The above object is accomplished generally by numbering the squares of checker boards and cutting slots in each square to receive the legs of an insert shelf, such shelf being of sufficient design and serving as a support for the game pieces or "men," and to retain the latter against accidental sliding across the board.

It is another object of the invention to provide an improved shelf to support checkers, chessmen or the like game pieces, even should the board be supported in a position just short of perpendicular.

A still further object of the invention is to provide a numbering system for the squares of the checker board in such wise as to facilitate the recording of the moves as made and to make it unnecessary to orient the board in any particular position for purposes of play.

A still further object of the invention is to produce an improved form of checker board which will enable two invalids in bed alongside each other to play competitively by each using his own individual board and making thereon not only his own moves but also duplicating his opponent's moves.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a top plan view of an improved checker board and shelf devices constructed in accordance with the present invention.

Figure 2 is an edge view of the same.

Figure 3 is a section, taken on an enlarged scale, on the line 3—3 in Figure 1.

Figure 4 is a similar view, on a slightly larger scale, showing the method of introducing one of the shelf feet into the slot and socket.

Figure 5 is a cross section taken on the line 50 5—5 of Figure 3.

Figure 6 is a perspective view of one form of the insert shown apart from the board.

Figure 7 is a fragmentary plan view of a game-board showing a modified form of pocket device.

2

Figure 8 shows a still further modified form of round hole in the board and peg foot of the shelf.

Referring more particularly to the drawings 10 designates a checker board of any approved form having squares 11 and 12 alternating and of dark and light contrasting colors, all in accordance with the conventional form of the checker board.

Ordinarily the dark squares are used for the playing surface and the game is conventionally 10 played crosswise of the center folding line 13 of the board. However as we wish to number the squares, and as numbers may not be so readily seen upon the dark surfaces of the squares 11, we preferred to turn the board so that the light 15 colored squares 12 may be employed for the game surface and to receive the game pieces and on which the game pieces are moved from one light colored square 12 to another. In order to accomplish this the board is turned at a 90° angle from 20 the position conventionally played so that the center folding line 13 is now perpendicular to the top and bottom of the board. By turning board 90°, line 13 supports board in perpendicular position. Otherwise, top half of board would fold 25 on bottom half when perpendicular.

In accordance with one phase of the invention the light colored playing squares 12 are marked with numbers in two sets, one pair of numbers to 30 each playing square 12. The numbers are in an arithmetical series beginning with the number 1 at the top of the board with the playing square 12 in the uppermost left hand corner, and proceeding transversely across the board in the top 35 row of playing squares, thence, as in the manner of reading, to the second horizontal column of squares beginning at the left edge of the board and progressing toward the right edge of the board. This sequence is continued, as indicated 40 clearly in Figure 1 until all thirty-two of the light colored playing squares 12 are numbered. The numbers are repeated in the upper corner portions of each square 12 so that either number may be clearly seen even if the other number is obscured by the checker or game piece owing to the fact that the player has carelessly moved it into an off center position on the square. Both dark and light squares should be numbered progressively so the board can be used for chess as well.

Then the board is reversed so that what was heretofore the top of the board now becomes the bottom and is toward the person who is inscribing the numeral system upon the board. This person then begins in the upper left hand corner of

the board and repeats the numbering system. Thus there are four numbers on each playing square 12. One number is in each corner of the square. Two of the numbers are relatively reversed to two of the other numbers so that the square originally numbered 1 is also invertedly numbered 32. This system of numeration makes the board reversible so that there is no top or bottom. In other words the board may be played from either end toward the player without the player having to select some particular edge of the board as the top. The board may be opened casually and does not have to be oriented to any particular position. All that the player need do is read the numbers which are upright to him. He disregards the inverted numerals. If the board is numbered for chess, then each square should have two slots or holes to receive Figure 6.

The board 10 is slotted as to each playing square 12, two slots 14 and 15 being made all the way through the board, one such slot at one side of each playing square 12 and the other slot 15 at the opposite sides. These slots are made at an intermediate portion of the square 12. With advantage they are made on a substantially median horizontal line through the square 12. At the bottom of the board each slot communicates with a lateral socket 16, 17 which socket opens downwardly through the lower face of the board but does not open through the upper playing surface of the board, there being shoulders 18, 19 forming the roofs or ceilings of the sockets 16, 17.

Insert pieces of shelf devices have legs 20, 21 with outturned feet 22, 23 adapted to be received in the slots and lateral sockets in the manner indicated in Figures 3, 4 and 5. For the purpose of facilitating insert and removal the upper free corner portions of the feet 22 are truncated or cut away, as indicated at 24 while similar cut away portions 25 are made at the inside bottom corner portions of the legs 21. These cut away portions give sufficient clearance for ease in inserting and removing the legs and feet as indicated in Figure 4.

Between the feet is a flexible shelf 26 which is longer than the distance between companion slots 14 and 15 so that when the legs and feet are engaged in these slots and their companion sockets, the shelf strip 26 is obliged to assume an arcuate or curved form as indicated in Figure 1. This forms a pocket for receiving the checkers 27, 28. The shelf 26 will be deep enough to receive two superimposed checkers as indicated in Figure 3 in the king position. The shelf 26 is preferably high in its central portion with its top edge rounded downwardly toward each leg 20, 21. The bottom edge of the shelf 26 will be flat or horizontal to lie throughout in its contact with the upper or playing surface of the checker board 10.

With a board numbered, slotted and socketed as to each of its playing squares 12, as above described, one foot 22 of a shelf is introduced down through the slot 14 and turned into the socket 16. Figure 4 shows the cut-away portions 24 and 25 simultaneously providing clearance for the corner portions of the slot and socket. In moving the foot 22 home into the socket 17, the shelf 26 will be rotated in a clockwise direction, as viewed in Figure 4, to bring its other foot 23 down toward the opposite slot 14, socket 16 into which it is introduced after the shelf strip 26 is flexed sufficiently to enable the leg 21 to assume a position over the slot 14.

Figure 5 shows the completion of the insertion, and Figure 1 shows the curved or flexed condition of the shelves 26 which may be made of paper, cardboard, mica, cellophane or any other desired material.

The length of each shelf strip 26 will preferably be such that when flexed it will describe an arc or semi-circle of a radius which will bring a curved shelf wall within the numerals so as not to obscure the same, although this is not particularly important as the shelf strips are flexed downwardly or toward the player and the lower numbers need not be read. These curved shelves are open at their upper sides to receive the checkers or game pieces. Checkers have rounded surfaces and the curvilinear shelves 26 are peculiarly adapted to receive and to retain the same no matter what the inclination of the board, it being understood that invalids in bed are not in position to have horizontal flat table supports for the boards but when the patient lies in a supine position in the bed the checker board may be held almost vertically with the checkers in the pockets and still the game may be conveniently played with fidelity without the checkers falling off the board or casually sliding from one space to another. The method of play is not in any wise altered or changed. Regular checkers can be used but chess might demand a new and different type of piece. A piece of cardboard cut so that it was a silhouette of each of the required chessmen or a regular chessman sawed in half through the perpendicular would be satisfactory provided the bottom was rounded to fit the shelf.

In use, two patients in beds alongside each other would each be provided with a separate checker board and with a complete set of checkers both for his own moves and for those of his opponent. His own "men" would be on the side of the board toward each player and the opponent's "men" would be on the upper side of each board, so that the game would assume a familiar aspect. The moves of the two opponents would simply be called across the beds from one another, using the numbers of the squares to announce the move. For instance one player would announce a move from 25 to 21 and the other would announce a move from 6 to 10. The players will shift the checkers in accordance with each announced move so that each player will have a complete replica of the game before him at all times of play.

As shown more particularly in Figure 8, a modified form of shelf is shown in which the foot is a round peg 20^a fitting in a round hole 14^a in the gameboard which round holes replace the slots at opposite sides of each playing square.

Referring more particularly to Figure 7 of the drawings, a modified form of shelf is shown in which a series of shelves 26^a are molded in one piece and extend the entire width of the board, being fastened to the edges of the board by appropriate pins or other fasteners 40. In this way slots in the board are eliminated and individual shelves are provided for each playing square. This would require eight such pieces 26^a, one for each row of playing squares, each piece being fastened so that it extends parallel to the top and bottom of the board.

It is obvious that various changes and modifications may be made in the details of construction and design of the above specifically described embodiment of this invention without departing from the spirit thereof, such changes and modifications being restricted only by the scope of the following claims.

What is claimed is:

1. An improved gameboard comprising a board having spaces, arcuate game piece shelf strips having legs and angular feet, said board having means to interlock with said legs and feet to hold the strips over the spaces at substantially a 90-degree angle with reference to the playing surface of said gameboard.

2. An improved gameboard comprising a board having spaces, each with two openings, one at 10 each side of the space, flexible shelf strips, each longer than the distance between said two openings, said strips having means to interlock in the openings and to hold the strips in curved form substantially perpendicular to the playing 15 surface of said gameboard.

3. An improved gameboard comprising a board having spaces, each with two openings, one of each side of the space approximately at the median portion thereof, said board having on its underside lateral shouldered sockets communicating with said openings, and flexible resilient game piece shelf strips having legs and outturned feet with truncated corner portions adapted to be detachably received into and interlocked with 20 25 said openings and sockets.

4. An improved gameboard comprising a board having spaces, each with two openings, one on each side of the space approximately at the me-

dian portion thereof, said board having on its underside lateral shouldered sockets communicating with said openings, and flexible arcuate game piece shelf strips having legs and outturned feet adapted to be detachably received into and interlocked with said openings and sockets.
